FRUIT JAR HOLDER

Edward J. Schwartz, Wilkinsburg, Pa.

Application April 16, 1935, Serial No. 16,600

3 Claims. (Cl. 81—33)

This invention relates to a container clamp, more particularly to a clamping device for holding fruit jars or the like while being filled with hot preserves, and more especially for placing the screw caps thereon.

It is among the objects of the invention to provide a clamping device for the above designated use which shall be of simple, compact and inexpensive construction and which shall embody a clamping mechanism to securely and safely clamp a glass jar or the like without danger of breakage or slippage.

In the drawing constituting a part hereof in which like reference characters designate like parts:

Fig. 1 is a plan view of a preserving jar clamp embodying the principles of this invention;

Fig. 2 is a side elevational view thereof;

Fig. 3 is a cross-sectional view partially in elevation taken along the line 3—3, Fig. 2; and

Fig. 4 is a plan view of a modified form of cam-lever.

With reference to the several figures of the drawing, the reference numeral 1 designates a base plate which is ribbed or corrugated at 2 to give it structural form with resulting rigidity and strength, thereby permitting the use of a relatively light gage metal. Mounted at one end of the base 1 which is enlarged for such purpose is a retaining band 3 that is riveted at 4 to up-struck portions or ears 5 that are integrally formed with the base 1. The strap or band 3 is preferably lined with a band 6 of non-metallic material such as rubber or a rubberized fabric to more intimately align itself to the contour of the jar 7 to be clamped. The base plate 1 is further provided with straps 8 that are secured thereto in spaced relation or which may be formed integrally therewith, the strips being in the shape of C clamps and are provided with thumb screws 9 by means of which the base 1 may be clamped to a support such as a table top designated by the reference numeral 10.

The base plate 1, for a portion of its length, is crimped or folded as shown at 11 to constitute ways or guides for a movable and adjustable clamping plate 12 having clamping jaws 13 integrally formed as up-struck portions at one end thereof, the opposite end being provided with an up-struck edge 14 that constitutes an abutment for the rounded end 15 of a lever 16. The jaws constitute clamping abutments that cooperate with the strap 3 to grippingly engage the container or jar 7. The jaws 13 are bulged as shown at 13a to give them structural form and strength, and

though rigid have a certain resilience to take up the clamping strain. Lever 16 is provided with a bent-over wing portion 17 constituting a grip for its manipulation and is further provided with a rivet 18 that is secured eccentrically of the rounded end 15 and is disposed in a hook-shaped slot 19 provided in the base plate 1.

In Figure 4 the lever 16 is shown as provided with a series of flat surfaces that are angularly spaced and which function to lock the clamping plate 12 in clamping engagement with the jar 7.

The operation of the above described jar holder or clamp is briefly as follows: The device is secured by fastening the C clamps 8 around the edge of a convenient support such as a shelf or table with the base plate 1 horizontally disposed.

The jar is placed against the stationary band 3 that constitutes a fixed though resilient abutment and by manipulating the lever 17 the clamping plate 12 slides in the direction of the jar 7 to intimately engage the latter. In the position of the lever shown in Fig. 1, the pivot or rivet 18 is in the extended position of the clamp for clamping jars of maximum diameter. Where a smaller jar is to be clamped, the pivot 18 of the lever is slid forward in the hook slot 19 and slipped into the terminus of the hooked end which moves the clamping plate closer to the stationary abutment a distance corresponding to the spacing of the hooked end with the position of the pivot as shown in Fig. 1. The lever is then operable in the manner explained to grippingly engage the jar of smaller diameter.

The lever 16 is shown as provided with a rounded end 15 for engaging the clamp abutment 14 and because of its eccentric mounting on the pivot 18, an intimate clamping effect is obtainable and the lever 16 is wedged in the locked position. However, the end of the lever, instead of being circular or rounded, may be provided with flat faces eccentrically disposed as shown in Fig. 4 to assure locking of the lever in the clamped position.

It is evident from the foregoing description of my fruit jar clamp that it is adapted to yieldingly and securely grip glass jars and lock them against rotation thereby enabling the user to securely apply the screw cap thereon. The structural form of the device permits the use of thin gaged metals which produce a light-weight structure, and the formation of the clamping jaws provides a large clamping surface which is resilient to a certain degree.

I claim:

1. A fruit jar holder comprising a base mem-

ber of relatively light-weight metal ribbed to constitute a structural section having integral lugs for anchoring an end abutment thereon and having bent-over parallel portions forming ways 5 for a movable clamp, a band of semi-circular form secured to said integral lugs and having a resilient liner thereon, a movable clamp disposed in the ways of the base member having clamping ears upstanding thereon constituting abutments 10 that coact with the band to grippingly engage a jar or the like, and a lever having a fulcrum pin slidably mounted in said base member and having an eccentric surface for engaging the movable clamp, said lever being adjustable relative 15 to the base to accommodate the clamp to different sized jars to be engaged thereby.

2. A jar holder as set forth in claim 1 said base member, having a hook-shaped slot for receiving the fulcrum pin of the lever, the terminals of said slot constituting anchorage abutments for said fulcrum pin whereby the clamping plate is 5 spaced from the stationary clamping abutment different distances corresponding to the spacing of the slot terminals.

3. A jar holder as set forth in claim 1 characterized by a cam-shaped lever having angularly spaced flat surfaces for engaging the clamping plate to lock same in clamped position. 10
